CLAIM

We claim the ornamental design for a meter housing, as shown and described.

DESCRIPTION

FIG. 1 is a perspective of a meter housing according to a first aspect of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective of a meter housing according to a second aspect of our new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken line portions of the figures represent unclaimed subject matter only and form no part of the claimed design.
